UNITED STATES PATENT OFFICE.

HENRY J. MENARD AND AUGUSTUS C. SAXTON, OF CHICAGO, ILLINOIS, ASSIGNORS TO
H. R. MANUFACTURING COMPANY, OF CHICAGO, ILLINOIS, A CORPORATION OF ILLINOIS.

LOCK FOR CONTROLLING LEVERS.

Application filed March 6, 1917. Serial No. 152,927.

To all whom it may concern:

Be it known that we, HENRY J. MENARD and AUGUSTUS C. SAXTON, citizens of the United States, and residing at Chicago, Illinois, have invented certain new and useful Improvements in Locks for Controlling Levers, of which the following is a specification.

This invention relates to locks for controlling levers, and is an improvement upon the invention described in our copending applications.

It is one object of the invention to so modify and rearrange the parts of our prior inventions that a lock operating upon somewhat the same simple, convenient and efficient plan may be applied to controlling levers in which the controlling lever is passed up from underneath through the transmission casing, and must be held up in actual operation.

It is another object of the invention to effect the automatic operation of a lever locking member when a member slidable upon the lever is pushed downwardly with the foot or otherwise, and an automatic release of the locking element when the key is turned in the lock, and to apply these principles of operation to a lever which must be supported or held up.

In the drawings:

Fig. 1 is a sectional elevation of a lock constructed according to our invention.

Fig. 2 is a sectional elevation of the same lock upon a plane at right angles to that of Fig. 1.

Fig. 3 is a detail sectional elevation of the lock.

Fig. 4 is a cross section upon the line 4—4 of Fig. 2.

Fig. 5 is a cross sectional elevation upon the line 5—5 of Fig. 2.

1 represents in general the transmission casing (of the Buick type, for instance,) in which is provided an interrupted spherical shaped casing, in which is mounted the ball 2 of the controlling lever 3, the lever being passed upwardly through the transmission casing, and supported upon the casing.

50 We provide a conical, preferably, shaped recess 4 in the transmission casing for the passage of the lever, and upon the controlling lever immediately above the ball 2 there-

of, we have mounted a slidable sleeve 5, having at its lower end an integrally formed disc 6, which has a taper to correspond with the taper of the conical shaped recess 4. Mounted on the substantially spherical outer surface 7 of the transmission casing is a correspondingly shaped cap member 8, having 60 the spherical flange 9. The member 8 performs the function of supporting the lever and simply moves over the top of the spherical casing as the lever is moved in operation in the fashion indicated in Figure 3. 65

Slidably mounted upon the upwardly extending sleeve 8' of the cap member 8, which is rigidly mounted upon the lever 3, is the lock casing 10, containing a spring pressed plunger 11, operated by means of a 70 cam 12, controlled by the tumbler lock 13, in a manner sufficiently obvious from the drawings. The sleeve 8' has near its upper end an annular notch 15, and near its lower end at least one aperture 16 of the size to 75 receive the bolt 11. The slidable casing 10 is mounted upon the sleeve 8', so that it may move freely up and down thereon, the construction being such that when the bolt 11 is retracted by means of the key operated 80 cam 12, the casing 10 is free to move up and down upon the sleeve 8', but when the casing 10 is moved downwardly (without turning the key) the bolt will spring into the aperture 16, locking the casing 10 in its 85 downward position. It will be noted that cap member 8 is under cut as indicated at 17, for the reception of the slidable lever locking member 5—6. Mounted upon the disc 6 of this member are a pair of vertically 90 extending bolts 20 which pass through holes drilled in the cap member 8 and into larger holes drilled in the slidable member 10, and are surrounded by the compression springs 21, bearing at one end against the heads 95 22 of the bolts, and at the other end against the top cap member 8. It will be noted that direct downward pressure can thus be communicated to the sleeve 5 of the disc shaped member 6 by pushing downwardly upon 100 the slidable casing 10, which is drilled out to accommodate the bolts 20 and surrounding springs. The swivel ends 23 of the drill holes in the casing 10 impinge directly upon the heads of the bolts and may thus positively push down the lever locking member 105

5—6. This locks the controlling lever by the engagement by plugging the conical recess 4 with the disc member 6, preventing the movement of the lever.

5 When the lock casing 10 has been pushed downwardly (the key, of course, being removed,) the bolt 11 automatically snaps into the recess 16 in the sleeve 8', absolutely locking the lever. When the key is inserted 10 and momentarily turned, the bolt 11 is retracted. The springs 21 then come into operation to automatically raise the locking case 10, in which event the bolt 11 rides upwardly and catches in the notch 15, preventing the lock casing from being pulled 15 up on the handle of the controlling lever, unless it is desired to do so, in which event the pressure upon the key is maintained, the bolt 11 being kept freely retracted so 20 that the lock casing may be raised as far as desired upon the controlling lever. In normal operation, however, the lock casing 10 will be caught by the notch 15, the springs 22 automatically pushing it up into 25 this position.

It is to be particularly noted that the disc member 6 when the key is momentarily turned is carried up by the same springs 21 which act upon bolts 22 and passes into a 30 formed seat in the bottom of the member 8, as shown in Figure 3, in which event it is well above the top of the spherical transmission casing 7 and cannot interfere with the operation of the machine.

35 It is, of course, obvious that it is not necessary to the realization of the major features of this invention, for the disc shaped member 8 to be provided with a conical face; a cylindrical member engaging in a cylindrical recess in the transmission casing would also serve, or the lower face 6' of the disc shaped member 6 could be made to directly abut the shoulder 2' of the lever and thus lock the same.

40 The construction just described affords a simple, compact, convenient, and extremely efficient lock for levers of the kind herein described.

45 Having now described our invention, 50 We claim:—

1. A lock for controlling levers comprising a lever locking element slidably mounted upon the controlling lever and adapted to lock the lever in one of its positions thereon, a cap member fixed to the lever for supporting the same, and means external to the cap member for automatically locking said lever locking member in locked position relative to said fixed member when the 55 lever locking member is moved to lever locking position.

2. A lock for controlling levers, comprising a member slidably mounted on the controlling lever, a member floating on the 60 transmission case but secured to the lever,

a lever locking device separate from and controlled by said slidably mounted member.

3. A lock for controlling levers, comprising a cap engaging the transmission case, 70 a lever locking member in said cap, and automatically operating means slidable on the controlling lever to lock said lever locking member in lever locking engagement in one position of said automatically operating means on the controlling lever.

4. A lock for controlling levers, comprising a lever locking member slidably mounted with respect to the controlling lever, another member separate from the lever locking member slidably mounted on the controlling lever, and means to automatically lock the lever locking member in lever locking 80 position when the second member is moved relative to the lever.

5. In a lock for controlling levers, a cap member fixed to the lever, a locking member slidable with respect to the lever and cap member, longitudinally movable means for transmitting motion to said locking 90 member, and means to prevent access to said last named means.

6. A lock for controlling levers, comprising a lever locking member slidably mounted with respect to the controlling lever and 95 adapted to lock the same in one of its positions thereon, a member fixed upon the lever, a second member slidable upon the lever, a connection between the second member and the lever locking member to cause the 100 latter to partake of movements of the former in one direction, and resilient means interposed between the fixed member and the lever locking member to move the same in another direction.

7. A lock for controlling levers, comprising a lever locking member slidably mounted with respect to the controlling lever and adapted to lock the same in one of its positions thereon, a member fixed upon the 110 lever, a second member slidable upon the lever, a connection between the second member and the lever locking member to cause the latter to partake of movements of the former in one direction, and means for automatically locking the second member to the lever at one point of its movement.

8. In a lever lock for automobiles having a ball lever, a cap member secured to the lever, adapted to fit upon the transmission 120 case and support the lever, a lever locking member slidable upon the lever and adapted to lock the lever in one of its positions thereon, a second member slidable upon the lever and adapted to be locked in respect 125 thereto in one of its positions thereon, and a connection between said second member and the lever locking member.

9. In a lever lock for automobiles having a ball lever, a cap member secured to the 130

lever, adapted to fit upon the transmission case and support the lever, a lever locking member slidable upon the lever and adapted to lock the lever in one of its positions thereon, a second member slidable upon the lever and adapted to be locked in respect thereto in one of its positions thereon, and a connection between said second member and the lever locking member, including resilient means to automatically force the second member into inoperative position when released.

10. In a lever lock for automobiles a member designed to support the lever, a slidable lever locking member, a slidable second member having therein a spring and key operated bolt, and adapted to automatically become engaged in locking relation with the supporting member when moved to one position with respect thereto, and a connection between the lever locking member and the second member, including resilient means to hold the lever locking member in inoperative position except when the second member is positively moved or held in one position.

11. In a lock for controlling levers, a lever support carried by the lever and fixed thereto, a lever locking member slidably mounted on the lever within the lever support, a slidable second member without the support, and adapted to become automatically locked thereto when moved into a certain position, connections between the second member and the lever locking member, to cause each to partake of movement of the other in one direction.

12. In a lock for controlling levers, a lever support carried by the lever and fixed thereto, a lever locking member slidably mounted on the lever within the lever

support, a slidable second member without the support, and adapted to become automatically locked thereto when moved into a certain position, connections between the second member and the lever locking member, to cause each to partake of movement of the other in one direction, and resilient means bearing against the lever support to move the lever locking member into inoperative position when released by the release of the second member.

13. In a control lever, a member fixed to the control lever and adapted to cooperate with the transmission casing for supporting the lever, a casing carrying a lock slidable on the fixed member, a slidable locking element on the lever within the fixed member, and means for automatically raising the sliding locking element in the slideable lock casing when the lock is disengaged.

14. In a lock for controlling levers, comprising a slideable casing carrying a lock, a separate locking element slideable upon the lever, a connection between the latter element and the slideable casing to cause the latter to partake of movement of the former in one direction, and means for automatically locking the locking element to the lever at one point of its movement. 70

In witness whereof, they hereunto subscribe their names to this specification in the presence of two witnesses.
